ADOLF GLASER
Inventor

By his Attorney Edwin Leisohn

UNITED STATES PATENT OFFICE.

ADOLF GLASER, OF NEW YORK, N. Y.

REMOVABLE BUTTON.

Application filed May 26, 1923. Serial No. 641,792.

To all whom it may concern:

Be it known that ADOLF GLASER, citizen of Roumania, having declared his intention of becoming a citizen of United States, residing at 115 East 92nd Street, city of New York, State of New York, % Wohlman, has invented new and useful Improvements in Removable Buttons, of which the following is a specification.

10 My invention relates generally to buttons and particularly to that type of button which may be readily attached to a garment without the use of thread or other fastening means than that forming a part 15 of the button itself.

Buttons of this type are constructed in many different ways and among the well-known varieties to be found on the market are those which comprise a body portion 20 having a depending pin portion arranged and designed along the general construction of a safety-pin. This particular arrangement has its disadvantages which are principally due to the way in which the pins are 25 mounted. The construction of an ordinary safety-pin is so well-known that it will suffice to call attention to the particular way in which the pin is embraced and held by guard shield at the head of the pin. The 30 length of the pin between the spring portion and the shield is unsupported and any undue strain brought to bear at the mid-portion thereof causes the latter to bow and the point finally is pulled out of the 35 guard shield.

Another disadvantage of the pins and buttons of this character now on the market is that the pin point is exposed and by reason thereof may catch into and tear the material or stick and scratch the wearer and 40 others.

With the above construction in mind it is the purpose of the present invention to provide a button of this type with a projecting pin which when engaged in the material to which the button is attached, the pin itself is supported at the mid-portion thereof and between the hinge for the latter and the curved pointed portion.

50 A further object of the present invention is to provide a button, the pin portion of which when in closed position is entirely enclosed within the body portion of the button itself.

55 I accomplished these purposes by provid-

ing the under surface of the button with a slot and a pin hinged at one end of the slot and the opposite end thereof provided with an ogee curve adjacent the point. This curve directs the point of the pin into the 60 opposite end of the slot at the middle of the button when the pin is engaged, and in order to hold the pin in engaged position a hook-shaped projection receives the portion of the pin adjacent the curved portion thereof, an 65 arrangement which prevents the pin from being pulled from the material or becoming disengaged from the hook-shaped projection.

The invention is illustratively exemplified in the accompanying drawing, in which, 70 Figure 1 is a substantially cross sectional view of my improved button taken on the line 1—1 of Figure 2; Figure 2 is a bottom plan view of the button showing the arrangement of a single pin, and Figure 3 is 75 a view of the button showing two fastening pins. Figure 4 is a detail perspective view of the ring to be applied to the pin at the under side of the material to prevent the pin from being pulled through the cloth. 80 Figure 5 is a modified form of pin showing the position of the free end of the pin when the latter is pulled perpendicularly with respect to the plane of the button. Referring to the drawings, 10 denotes a curved 85 button shield having a closed straight bottom wall 11 provided with a radially disposed slot 12 extending slightly beyond the center of the wall 11. A pin 13 is secured at its straight end to the end of the slot adjacent the edge of the curved shield portion 10, and the opposite end thereof is provided with an ogee curved portion 14 which enables the straight portion of the pin 13 to be disposed parallel to the walls of the slot 12 while the downwardly directed portion 90 of the curve below the plane of the bottom wall 11 and the point 15 projects into the body of the hollow shield 10. The slot is slightly wider than the diameter of the pin 13 and the mid-portion of the bottom wall 11 and disposed on one wall of both walls of the said slot 12 is a hook-shaped projection 16 which is adapted to receive the pin 13 adjacent the beginning of the curved portion 14 thereof and between the latter and the attached end of the pin.

100 In Figure 3, the construction of the individual pins 13 is similar to that already described and the only change in construction 105 110

is in the position of the slots 12, one being arranged on each side of a diameter of the shield 10.

In attaching a pin according to the present construction the pin 13 is outwardly swung from the slot and inserted through the material so as to bring a portion of the latter in the downwardly directed curved part 14. The point 15 of the pin 13 is then inserted 10 in the slot and the part between the hinge and the curve portion 14 is engaged over the hook 16. It will be clear from this disclosure that any pull exerted by trying to draw the material away from the pin will 15 merely cause the curved portion 14 to engage more closely over the inner surface of the bottom wall 11 at the end of the slot 12.

It may be, in some instances, found desirable to provide means to be attached to 20 the loop 14 of the pin 13 below the material so as to prevent the pin from being pulled out of the cloth, as for instance, where very heavy material, or cloth is employed, such means comprising a ring 17 25 bent or otherwise produced from a piece of wire or other suitable material and having a portion thereof bent diametrically across the center in the shape of a U curve 18. The

space between the parallel walls of the curve 30 18 is adapted to receive the projecting portion 14 of the pin 13 below or behind the material. The application of the ring 17 is shown particularly in Figure 1.

Having described my invention what I claim and desire to secure by Letters Pat- 35 ent is:

In a button, the combination of an integral crown portion and flat bottom wall, the latter having a single radial slot, one wall thereof having an inwardly disposed 40 tongue, a pin pivoted at one end at the interior of the button and at the extreme outer end of the slot, the free end of the pin being bent in an ogee curve outwardly from the said flat wall and having its ex- 45 treme end bent upright at right angles to the axis of the straight portion of the pin, and an annular locking member having a lateral U-shaped midportion provided with notches to embrace the upright end and the 50 ogee portion of the pin, substantially as described.

In testimony whereof, ADOLF GLASER has signed his name to this specification, this 15th day of May, 1923.

ADOLF GLASER.
